PHOTOELECTRIC GENERATOR

Walter Schottky, Berlin-Charlottenburg, Germany, assignor to Siemens & Halske, Aktiengesellschaft, Siemensstadt, near Berlin, Germany, a corporation of Germany

Application May 1, 1929, Serial No. 359,704
In Germany May 2, 1928

3 Claims. (Cl. 136—89)

My present invention relates to a light-sensitive device adapted to transform variations in light intensity into variations of an electric current. It has been proposed hitherto to construct photoelectric generators comprising a layer of cuprous oxide upon copper, this oxide layer having a rectifying effect in connection with the copper, a light-pervious electrode being arranged on the free or exposed surface of the cuprous oxide layer. The light passes through this electrode and through the cuprous oxide layer and impinges upon the surface at which the copper is in contact with the cuprous oxide, a photoelectric current being thus produced. This device of the prior art suffers from the very serious drawback that the cuprous oxide layer absorbs light very strongly, and that in a selective manner with respect to different colors, so that with light of a given intensity the photoelectric current effect obtainable theoretically is very much impaired in practice.

According to my present invention, the metal or electrode which together with the layer of cuprous oxide or of other semi-conductor produces the rectifying effect, is made pervious to light. I thus secure the result that the light passing through such electrode will reach practically undiminished the contact surface between the said metal and the said semi-conductor layer; the current produced by photoelectric action will therefore be relatively large.

The layer of semi-conductor may be a layer of cuprous oxide which may be produced upon a copper base or electrode. In this case the copper should be readily pervious to light, that is, it should be produced, by any well known or approved method, of such thinness that it will be of glass-clear transparency.

Reference is to be had to the accompanying drawing in which the figure is a sectional view of a photoelectric cell embodying my invention.

For the sake of greater clearness, the thicknesses of the several elements of the cell have been exaggerated in the drawing.

The photoelectric cell, adapted to receive light

from a light source 4 from the left as indicated by the arrows, comprises a metallic conductive electrode 1, of copper, for example, and preferably in the form of a thin metal foil, which is readily pervious to light, and preferably of glass-clear transparency.

On this electrode 1 there is applied or produced, for example, a layer 2' of cuprous oxide, so that this semi-conductive layer forms with the electrode 1 a rectifying connection.

The electrode 1 preferably is made with a reinforced edge. The light from the light source 4 passes through the electrode 1 and impinges in practically undiminished force on the contact surface between the electrode and the cuprous oxide layer. A metal conductive electrode 3' is provided on the other side of the semi-conductor 2'.

The light-pervious metallic conductive electrode 1 may be provided with grid-like reinforcing ribs 8, which at the same time cause better conduction of the current from the thin metallic electrode 1. These grid-like reinforcing ribs 8 may be integral with the thin metallic electrode 1.

I claim:

1. A photo-electric generator comprising two metallic conductive electrodes and a semi-conductor layer located between them, said semi-conductor layer being of cuprous oxide, the electrode on the light receiving side of said photo-electric generator being of copper and in intimate contact with substantially all of one surface of the semi-conductor and producing a rectifying effect therewith, said electrode being of such thinness as to be pervious to light.

2. A photo-electric generator as claimed in claim 1 in which the light pervious electrode is reinforced by ribs.

3. A photo-electric generator as claimed in claim 1 in which the light pervious electrode is reinforced by grid-like ribs integral with said electrode.

WALTER SCHOTTKY. 45
